UNITED STATES PATENT OFFICE.

CARL J. SCHWARZE, OF ADRIAN, MICHIGAN.

ELECTRIC BELL.

1,091,898.

Specification of Letters Patent. Patented Mar. 31, 1914.

Application filed September 11, 1912. Serial No. 719,766.

To all whom it may concern:

Be it known that I, CARL J. SCHWARZE, a citizen of the United States of America, residing at Adrian, in the county of Lenawee and State of Michigan, have invented 5 certain new and useful Improvements in Electric Bells, of which the following is a specification, reference being had therein to the accompanying drawings.

10 The invention relates to electric bells and is more particularly applicable to that type known as single stroke bells.

It is the object of the invention to obtain a simple and efficient construction, in which 15 a large bell may be operated with small expenditure of energy.

To this end the invention consists, first, in the peculiar construction of a pendulum hammer and operating mechanism therefor, 20 and further in various features of construction as hereinafter set forth.

In the drawings: Figure 1 is a front elevation showing the pendulum hammer and operating mechanism; Fig. 2 is a perspective view of a portion of the mechanism; 25 Fig. 3 is a plan view; and Fig. 4 is a side elevation with the cover in section.

A is a suitable frame or bracket, upon which is mounted the bell B.

30 C is the electro-magnet for operating the bell, which is mounted within a recess in the upper portion of the frame A.

D is a hinged armature which is mounted in a bracket E upon vertical pivots F and F', and is adapted to be moved laterally whenever the magnet is energized.

The hammer for the bell is in the form 40 of a pendulum, which is hung upon and carried by the armature D. This pendulum G is fulcrumed upon a horizontal pivot H, secured to the bracket E, but the weight of the pendulum is sustained by the hinged armature. As shown, the pendulum has at its upper end the laterally bent portion I, 45 which engages bearings in ears J upon a member K, which is sleeved upon a vertically extending pin L on the armature. Upon the fulcrum pivot H is sleeved a member M, having ears N slidably engaging the 50 downwardly extending portion of the pendulum. Thus whenever the magnet is energized and the armature swung upon the vertical pivots F, the pin L and member K will actuate the bent portion I of the pendulum G, while the pivot H and member M will determine its path of movement. On

account of the sliding engagement between the pendulum rod and the ears N of the member M, and also the slidable engagement between the laterally bent portion I 60 and the ears J, the pendulum will move without any binding, due to the difference in directions of movement of said parts. Thus the member K being supported upon the armature will move therewith in a horizontal plane, carrying the portion I of the pendulum through a similar path. On the other hand, the member M will move angularly about the pivot H, imparting to the ears N a movement through a segmental 70 path; consequently there will be a longitudinal sliding movement of these ears upon the pendulum rod. In the same way the angular movement of the pin L and member K about the axis of the pivots F will cause 75 a sliding of the ears J upon the portion I, the effect being to produce a universal coupling between the pendulum and the armature, which avoids all binding and friction 80 of the parts. The lower end of the pendulum is provided with a suitable hammer-head O, which under the pull of the armature will impinge against the bell and produce the sound. The magnet, armature and connecting mechanism is housed by a casting P secured to the frame A, and having a skirt Q overlapping a portion of the bell. 85

What I claim as my invention is:

1. In a bell, the combination with an electro-magnet, of a pivoted armature, a pendulum hammer supported upon said armature, 90 a stationary fulcrum, and universally pivoted connections between said pendulum and armature and pendulum and fulcrum.

2. In a bell, the combination with an electro-magnet, of a pivoted armature, a pendulum hammer supported upon said armature and movable therewith, a fixed fulcrum, and connections between said pendulum and armature and pendulum and fulcrum, permitting 100 a universal movement between the pendulum and armature.

3. In a bell, the combination with an electro-magnet, of an armature therefor supported upon vertical pivots, a pendulum hammer supported upon said armature, a stationary fulcrum and universally pivoted 105 connections between said pendulum and armature and pendulum and fulcrum.

4. In a bell, the combination with an electro-magnet, of an armature therefor supported upon vertical pivots, a pendulum 110

hammer having a laterally extending portion supported upon said armature and movable therewith, a fulcrum pivot, and a slideable connection between said fulcrum and pendulum.

5. In a bell, the combination with an electro-magnet, of an armature therefor supported upon vertical pivots, a pendulum hammer having at its upper end a laterally bent portion, a member slidably engaging said laterally bent portion of the pendulum, and vertically pivoted upon and supported by said armature, a stationary fulcrum pivot, and a slideable connection between said fulcrum and pendulum.

10. 6. In a bell, the combination with an electro-magnet, of a hinged armature supported upon vertical pivots, a vertically extending pin on the free end of said armature, a member pivoted on said vertical pin and extending laterally therefrom, a pendulum hammer having a laterally bent portion slidably and pivotally engaging bearings in said laterally extending member, a stationary 25 fulcrum pivot, a member sleeved upon said pivot and having a bearing slidably engaging said pendulum.

20. 7. In a bell, the combination with an electro-magnet, of a hinged armature supported upon vertical pivots, a pin extending vertically from the free end of said armature, a horizontally extending fixed fulcrum pin, members respectively pivoted upon said vertical and horizontal pins, and provided with 25 transversely extending bearings, and a pendulum hammer having a laterally extending portion slidably and pivotally engaging a bearing on one of said members, and having

a depending portion pivotally and slidably engaging the bearing on the other of said 40 members.

8. In a bell, the combination with an electro-magnet, of an armature therefor supported on vertical pivots, a pendulum hammer having a laterally bent portion at its upper 45 end, a member engaging a vertical pivot on the free end of said armature, having a laterally extending portion with struck-up ears for pivotally and slidably engaging said laterally extending portion of the pendulum, 50 a horizontally extending, fixed fulcrum pin, and a member sleeved upon said fulcrum pin having a laterally extending portion provided with struck-up ears pivotally and slidably engaging the depending portion of said 55 pendulum hammer.

9. In a bell, the combination with a frame, a sound-producer mounted thereon and an electro-magnet mounted on said frame above said sound-producer, an armature mounted 60 on vertical pivots on said frame, a pendulum hammer having a laterally bent portion at its upper end, a horizontally extending, stationary fulcrum for said hammer, universal, pivotal connections between said laterally 65 extending portion of said hammer and said armature, and between the downwardly extending portion of said hammer and said fulcrum pin, and a housing for inclosing 70 said parts and overlapping said bell.

In testimony whereof I affix my signature in presence of two witnesses.

CARL J. SCHWARZE.
